UNITED STATES PATENT OFFICE.

PERCY B. BOSWORTH, OF BROOKLYN, NEW YORK, ASSIGNOR OF ONE-HALF
TO CHRISTIAN BAECHTOLD, OF SAME PLACE.

AUTOMATIC VENDING APPARATUS.

SPECIFICATION forming part of Letters Patent No. 402,800, dated May 7, 1889.

Application filed February 13, 1889. Serial No. 299,726. (No model.)

To all whom it may concern:

Be it known that I, PERCY B. BOSWORTH, of Brooklyn, in the county of Kings and State of New York, a citizen of the United States, 5 have invented certain new and useful Improvements in Automatic Vending Apparatus, of which the following is a specification.

This invention relates to an improved vending apparatus of that class in which a merchandise-delivery slide is released by the dropping of a coin into a coin-chute; and the invention consists of a vending apparatus the casing of which is provided with a merchandise-delivery chute, a recessed delivery-slide 15 guided in said casing and provided with a slot that registers with a slot of the casing and the delivery-opening of the coin-chute, a coin-chute attached to the delivery-slide and twisted from a transverse position at its upper end into a vertical position at its lower end, a pivoted locking-lever the shank of which is guided in a recess of the coin-chute, while its recessed upper part engages a fixed lug of the delivery-slide, and a pendent gate 20 hinged to the delivery-slide and forming contact with the channel at the upper part of the coin-chute, so as to prevent the withdrawal of coins or other devices that are introduced into the coin-chute for tampering with the locking mechanism.

The invention consists, further, of additional elements and details of construction, which will be fully described hereinafter, and finally pointed out in the claims.

35 In the accompanying drawings, Figures 1 and 2 represent vertical longitudinal sections of my improved automatic vending apparatus, showing the same respectively in a normally-locked position and in open position, 40 with the delivery-slide drawn out and released from the locking mechanism; and Figs. 3 and 4 are vertical transverse sections, respectively, on line $\alpha\alpha$ and yy , Fig. 1.

Similar letters of reference indicate corresponding parts.

In the drawings, A represents the casing of my improved automatic vending apparatus, which is provided with a larger lower part, A', and with an upper smaller part, A², in

which latter the merchandise-delivery chute or chamber B is located. A horizontal partition, a, divides the upper and lower parts of the casing A, said partition being provided at the interior of the casing A with a recess, a', for the U-shaped rear end of the delivery-slide 50 C. The rear part of the delivery-slide C is guided in the recess a' of the partition a, the upper end of the U-shaped rear part of the delivery-slide being guided in a recess, b, of the front wall upper part of the casing A at 55 the lower end of the delivery-chute B. The front end of the U-shaped rear part of the delivery-slide C is flanged, so as to close the recess in the front wall of the upper part of the casing A, as shown clearly in Fig. 1. 60

The rear part of the delivery-slide C is provided next adjoining the flange, at the front end, with a recess, d, which corresponds in size to the delivery-opening of the chute B and the merchandise that is fed from said chute 70 B on the partition a below the chute B and recess d', so that the merchandise in the chute B—such as confectionery—may be supplied one at a time into the recessed rear part of the delivery-slide and moved in forward direction with the same, so as to be dropped onto the lower part, A', of the casing in front of the upper part, A², as shown in Fig. 2. The main part of the delivery-slide C extends 75 through an opening in the front wall of the lower part of the casing A to the outside, and is provided with a knob or hook by which it is pulled in outward direction whenever the locking mechanism of the delivery-slide is released. 80

To the rear wall of the lower part of the casing A, and to the rear end of the delivery-slide C, is attached a helical spring, C', which serves to return the delivery-slide C into its normal position after it has been pulled out. 90 In the top of the lower part, A', of the casing A, and vertically above a slot, e', in the front end of the delivery-slide, is arranged a transverse slot, e, for dropping the coin by which the locking mechanism is released. The slot 95 e registers with the slot e' in the delivery-slide C, and with the upper opening of a coin-chute, E, which is attached to the under side

of the delivery-slide C. The upper part of the coin-chute E is arranged in vertical position transversely to the delivery-slide C, while the middle part of the coin-chute A is twisted, 5 so that the lower end assumes a vertical position parallel with the side walls of the casing A, as shown clearly in Figs. 1 and 2.

Adjoining the upper part of the coin-chute E and back of the same is hinged to the under side of the delivery-slide C a pendent gate, E', which forms contact at its lower end with the middle part or channel of the coin-chute E, and which is moved back whenever a coin is dropped into the coin-chute, but 15 which is instantly returned into contact with the coin-chute when the coin has moved past the gate. The gate E' prevents the withdrawal of any coin, wire, or other implement inserted into the coin-chute with a view of 20 releasing the locking mechanism, but without paying the proper equivalent for the merchandise delivered. The pendent gate serves thus as a safety device by which tampering with the vending apparatus is prevented.

25 To a bracket-arm, f, attached to the rear wall of the casing A, is fulcrumed a locking-lever, F, which engages by its recessed upper part or latch a fixed lug, f', at the under side of the delivery-slide C, while the lower end 30 or shank of the lever F is guided in a recess, f², in the upper edge of the lower end of the coin-chute E, as shown clearly in Fig. 1. The shank of the lever F is made in the shape of a wire of the thickness of the coin required 35 for releasing the locking-lever, said shank being guided in the lower end of the coin-chute in following the pressure of the coin on the same.

40 A guard-hook, G, is pivoted to a bracket-arm, g, sidewise of the coin-chute E, and intended for the purpose of preventing the shank of the locking-lever swinging too far backward in case the vending apparatus is not supported in horizontal position. The 45 pivoted guard-hook G prevents the clearing of the wire shank of the locking-lever from the lower end of the coin-chute and forms a second safeguard by which the proper working of the releasing mechanism is secured.

50 The operation of my improved vending apparatus is as follows: When a coin is dropped through the coin-slot at the front part of the casing A, it is passed through the slot of the delivery-slide into the upper transverse part 55 of the coin-chute, then by gravity in downward direction, so as to push the hinged gate aside and roll with considerable momentum into the lower vertical part of the coin-chute, where it strikes against the wire shank of the 60 locking-lever, so as to move the same backward and release the latch from the lug of the delivery-slide C, as shown in dotted lines in Fig. 1, whereby the latter can be drawn in forward direction, so as to deliver a piece of 65 confectionery or other article of merchandise to the front part of the casing, whence it is removed by the party who has dropped the

coin into the apparatus. As soon as the delivery-slide is moved forward the coin which has been retained in the lower end of the coin-chute by a block or abutment on the rear wall of the casing is dropped to the bottom of the casing as the coin-chute is also moved forward and provides sufficient space between its lower end and the abutment for the dropping of the 70 coin. The twisted shape of the coin-chute has the advantage that the coin passes from a vertical transverse position to a vertical position parallel with the side walls of the casing, by which tampering with the apparatus 75 is prevented, as it does not permit the drawing back of the coin when once dropped. The twisted coin-chute also serves to retard a sheet-metal disk of less weight than the coin required for releasing the locking-latch, which 80 thereby arrives at the lower end with less momentum, so as not to overcome the inertia of the locking-lever and release the same from the lug of the delivery-slide. It thus appears that a high degree of security against tampering with the vending apparatus is obtained 85 by the coin-chute in connection with the pendent gate at the upper part of the same and the guard-hook that works in connection with the wire shank of the locking-lever at the lower 90 end of the coin-chute. As the vending apparatus is made of comparatively simple construction, it can be made at a comparatively small expense and can thereby compete with similar vending apparatus in the market. 95

Having thus described my invention, I claim as new and desire to secure by Letters Patent—

1. The combination of a merchandise-delivery chute, a guided and spring-actuated delivery-slide having a recessed rear part 105 vertically in line with the delivery-chute, a coin-chute attached to the delivery-slide vertically below a coin-slot in the casing, a locking-lever below the delivery-slide, the shank of which is guided in the lower end of the 110 coin-chute, and a fixed lug at the under side of the delivery-slide that is engaged or released by the latch of the locking-lever, substantially as set forth.

2. The combination of a guided and spring-actuated delivery-slide having a slot registering 115 with a coin-slot in the casing of the apparatus, a coin-chute attached to the delivery-slide below the slot of the same, said chute being twisted so that its lower end assumes a vertical position, a fulcrumed locking-lever having a latch, a shank extending into the recessed lower end of the coin-chute, and a lug at the under side of the delivery-slide, substantially as set forth.

3. The combination, in an automatic vending apparatus, of a guided and spring-actuated delivery-slide having a slot registering with the coin-slot of the casing of the apparatus, a coin-chute attached to the delivery-slide below the slot of the same, said coin-chute being twisted so that its lower end assumes a vertical position, and a pendent gate hinged to the delivery-slide back of the 130

upper transverse part of the coin-chute, so that its lower end forms contact with the same and serves to arrest any coin, wire, or other device introduced for tampering with 5 the releasing mechanism, substantially as set forth.

4. The combination of a casing, a delivery-slide guided in said casing, a twisted coin-chute attached at its upper end to the delivery-slide and having a lower vertical end, a fulcrumed locking-latch engaging a fixed lug of the delivery-slide and having a wire shank extending into the lower vertical end of the coin-chute, and a pivoted guard-arm 15 that prevents the shank of the locking-lever from passing to the outside of the coin-chute, substantially as set forth.

5. The combination of a casing having a merchandise-delivery chute in its upper part

and a coin-slot, a guided and spring-actuated 20 delivery-slide having a U-shaped and recessed rear part and a corresponding coin-slot, a twisted coin-chute attached to the delivery-slide, a locking-lever having a latch at its upper end and a wire shank at its 25 lower end, said wire shank engaging the recessed lower end of the coin-chute, and a lug at the under side of the delivery-slide for locking or releasing the slide, substantially as set forth. 30

In testimony that I claim the foregoing as my invention I have signed my name in presence of two subscribing witnesses.

PERCY B. BOSWORTH.
